UNITED STATES PATENT OFFICE.

SAMUEL NEVIN HENCH, OF YORK, PENNSYLVANIA

CULTIVATOR.

SPECIFICATION forming part of Letters Patent No. 785,038, dated March 14, 1905.

Application filed September 28, 1904. Serial No. 226,353.

To all whom it may concern:

Be it known that I, SAMUEL NEVIN HENCH, of York, in the county of York and State of Pennsylvania, have invented certain new and useful Improvements in Cultivators, of which the following is a specification, reference being had to the accompanying drawings, in which—

Figure 1 is a plan view of a walking-cultivator of the straddle-row type embodying my improvements in their preferred form. Fig. 2 is a rear end elevation of the same. Fig. 3 is a section on line 3 3, Fig. 2. Fig. 4 is a side elevation of the cultivator with the drag-bars or shovel-beams nearly down. Fig. 5 is a like elevation of the same with the parts in the position they occupy when the drag-bars or shovel-beams are thrown up. The remaining figures (6 to 10, inclusive) are views, on enlarged scale, of structural details. Fig. 6 is a perspective view of one end of the arch-beam, the sleeve thereon to which are jointed the supporting arms or rods by which the shovel-beams are permitted "parallel motion" to and from each other, the lever-arm thereon, which carries the wheel-spindle or stub-axle, and the spindle itself, all of these parts being shown detached from one another, but still associated in approximately their relative positions. Fig. 7 shows the spindle-carrying lever and the parts immediately connected with the same in three positions. The position shown in full lines is that which it occupies when the shovel-beams are down, so that the shovels rest on the ground, as in Fig. 4. The position shown in dotted lines to the left is that which it occupies when the shovels are down in the soil, and the position shown in dotted lines to the right is that which it occupies when the shovel-beams are thrown up, as in Fig. 5. Fig. 8 is a perspective view of a part of one of the shovel-beams, showing the means employed for connecting therewith the two arms by which the beam is coupled to the arch-beam. Fig. 9 is a horizontal longitudinal section of these parts on line 9 9, Fig. 10. Fig. 10 is a section on line 10 10, Fig. 9.

My improvements have principally to do with the means for coupling the drag-bars or shovel-beams to the arch-beam or other part of the frame to which they may be connected

and for preventing lost motion and taking up wear therein and with the devices and combinations of devices by which the drag-bars may be thrown up or down and held in either position and also by which when the drag-bars are down their pressure in downward direction may be regulated at pleasure, so as to cause the shovels which they carry to act upon the ground with more or less vigor, as desired.

The arch-beam consists of two like bars or rods A, of L form approximately. Their upper and inner ends overlap and are held in stirrup-bearings *a* on the under side of the limbs of the divided tongue B, the stirrup-bearings being drawn by nuts *b* on their upper ends, which protrude through the limbs of the tongue so as to clamp and bind the parts rigidly and securely together. The purpose of this divided arrangement of the arch-beam is, as is well known, to permit the two parts of the beam to be adjusted in such manner as to set the wheels near together or farther apart, as desired. The outer ends of the divided arch-beam are cylindrical in cross-section, and upon each of them is fitted a sleeve C and the upper end of an arm D, both of which can turn upon the outer end of the beam as an axis. The sleeve and arm when in action are rigidly secured together and move together, and, indeed, they may be formed in one or immovably fastened together, if desired. I prefer, however, to fasten them together adjustably for purposes hereinafter indicated. Each arm D carries the spindle or stub-axle E, Fig. 6, on which one of the two, 85 wheels W of the machine is mounted, and each sleeve C is jointed to the pair of coupling-arms F G which belong to the drag-bar or shovel-beam H on the same side of the machine with the sleeve, each beam carrying suitable shovels S and a guard-wheel T of suitable construction. Each main coupling-arm F is jointed to its sleeve C by means of a vertical joint pin or bolt *f*, which passes through holes in the limbs of the front forked end of 95 the arm and through a vertical socket or hub *c* on the sleeve, which fits between the limbs of the fork and is there held by a nut *f'*. The front end of the coupling-arm F is thus swiveled to the sleeve C on a vertical axis, while 100

the sleeve itself is mounted to turn upon a horizontal axis. Each supplemental coupling-arm G is also swiveled to its sleeve C on a vertical axis, the sleeve being provided for 5 the purpose with a vertical hole or socket c' in a horizontal flange c^2 on the side of the sleeve, down through which protrudes the front hook end g of the coupling-arm G, Figs. 1 and 2, which swivels in the socket and is held there- 10 in by a cotter-pin g' or the like. The rear ends of the main coupling-arm F and the supplemental coupling-arm G are also swiveled to their drag-bar or shovel-arm H, each on a vertical axis. The particular means there em- 15 ployed for this purpose will be presently described.

Each spindle or stub-axle E is preferably fastened to its supporting-arm D by having one of its ends inserted into a split ring or 20 hub e , formed on the lower end of the arm and there held tightly in place by closing upon it the split ring by means of a clamping nut and bolt e' , which engages ears e^2 on the ring in the usual way.

25 The heads of the spindle-carrying arms D are enlarged and are provided with holes engaged by the usual shackles o of the whiffle-tree connections and stay-rods p , which extend thence to a cross-bar B' on the main frame, 30 to which they are fastened. Other stay-rods, p' , have eyed ends which fit on the lower horizontal portions of the arch-beam at the point where those portions join the vertical limbs of the arch-beam (as seen, for example, in Fig. 3) and extend up to and are bolted to the 35 cross-beam.

The drag-bars H are provided with handles K of any usual or suitable construction. Each drag-bar is held down to its work with yielding pressure exerted by a spring I, (in this 40 instance a spiral spring,) which is attached at its front end to an eye i on the cross-beam B' and at its rear end to a link J, which in turn passes around and engages a notched bar f^2 , 45 projecting downward from the under side of the main coupling-arm F. In the intermediate position in which the drag-bars are shown in the drawings the points 1 and 2, Fig. 3, at which the spring I and its link J are sever- 50 ally connected to the cross-bar B' and coupling-arm F, are in a straight line, which practically intersects the axis of oscillation of sleeve C, to which the front end of coupling-arm is attached; but when the drag-bars are pressed 55 down by their handles so as to bring the points 1 2 in a straight line which passes below the axis of oscillation of sleeves C then the springs I, through the links J and bars f^2 , exert a downward pull upon the coupling-arms with 60 the effect of holding down the drag-bars to their work with yielding pressure. The notched bars f^2 are provided with a series of notches f^3 , so that by engaging the links with the selected notches the downward spring 65 pressure or pull can be varied and regulated

as desired. On the other hand, when it is desired for any reason to throw the shovels out of action all that is needed is to lift the drag-bars by their handles until the points 1 and 2 are in a straight line which passes above the 70 axis of oscillation of the sleeves C. The pull of the springs I then lifts the drag-bars to the position shown in Fig. 5 and holds them there. The front end of each drag-bar when in this position passes between a pair of spring-clips 75 L, one on the rear end of each limb of the divided tongue, which serve to assure the drag-bars in their raised position. It will be noted by reference to Fig. 5 that in this operation of throwing up the drag-bars not only are 80 they raised, but the arch-beam and main frame drop, the weight of the latter thus assisting in the operation and measurably lightening the work of the springs. This feature I believe to be new with me beyond its special 85 structural embodiment herein illustrated.

As hereinbefore indicated, I prefer to adjustably connect each sleeve C with its arm D, the object being to provide a means for varying the pitch of the shovels so that, for instance, either the front or the rear shovel will run a little deeper or shallower, as required. To this end in arm D, below the hole through which passes the horizontal outer end of the arch-beam, is a series of holes d , in this instance three in number, which are formed in the arc of a circle of which the axis of oscillation of the arm D, is the center. These holes are preferably formed, as shown, as squared openings in a slot in the arm D, through one 90 or the other of which will pass the squared portion of the shank of the bolt d' , by which the arm is held to the sleeve C, the latter being provided at its inner end, which fits up against the arm D, with a radial enlargement 95 C', in which is formed the hole d^2 , through which protrudes the screw-threaded end of the bolt d' , upon which the holding-nut is to be screwed. By passing the bolt d' through one or the other of the holes d the sleeve C 100 necessarily will be partly rotated in one direction or the other, with the result of slightly lifting or lowering the front end of the drag-bar to which it is connected, and thus correspondingly changing the pitch of the shovels. 110

It remains to describe the means for securing the coupling-arms to their drag-bars, having more particular reference to the devices used for this purpose in connection with the main coupling-arms F, which take most of 120 the strain.

Each drag-bar H consists (as in my prior Patent No. 684,571, of October 15, 1901) of two parallel bars h , provided with longitudinal rows of perforations h' in their webs 125 through which pass the bolts which clamp the shanks of the shovels S between the bars h , these bolts passing through or engaging split boxes, the parts of which encircle the shovel-shanks and are clamped thereto by the action 130

of the bolts in the usual way. One of the bars h extends out in front a proper distance beyond the other to furnish a bearing for a guard-wheel T . The forked rear end of each 5 main coupling-arm is jointed to a coupling-pin which is also inclosed in a longitudinally-split box clamped between the bars h of the drag-bar H , to which it pertains. This coupling-pin or stem in the present instance is 10 part of one of the shovel-shanks, which is suitably formed for this purpose, as indicated at s , Fig. 10. It has a shoulder s' on its lower end, on which rests the collar s^2 , and its upper end is screw-threaded to receive the tightening-nut s^3 . Encircling the stem s is a longitudinally-split box M , having an interior to fit the stem and having squared exterior faces m to fit against the bars h , between which the box is placed, and with ears m' , having slots 15 or perforations for the passage of the bolts m^2 , by which the divided box and stem are firmly clamped to each other and to the drag-bar, as seen in Figs. 8 and 9. The upper and lower ends of the divided box are conical, as 20 seen at n , and the perforated limbs f^2 of the divided rear end of the main coupling-arm (see Figs. 8 and 10) encircle and swivel upon the coupling-stem s as an axis and are received the lower one between the collar s^2 25 and the conical lower end of the split box M and the upper one between the nut s^3 and the conical upper end of the split-box M . The 30 holes or perforations in the limbs f^2 , through which the coupling-pin or stem s passes, are 35 conical, as seen at f^3 , Fig. 10, to fit the conical ends n of the box M and to form, in conjunction with the same, cone-bearings for the swiveled rear end of the main coupling-arm. F. In this way I am enabled to avoid all lost 40 motion, to readily compensate for and take up wear and tear, to preserve in the joint the strength requisite to enable it to resist the strain which necessarily comes upon it in the operation of raising and lowering the drag-bar, and at the same time to assure the swiveling action which is requisite to easy lateral movement of the drag-bars and their shovel-gangs whenever required.

The rear end of the supplemental coupling-arm G is formed as a hook g^2 , which enters and passes down through a socket in a bearing-block O , Figs. 8 and 9, in which socket it swivels and is held by a cotter-pin g^3 . The block O is bolted to one of the I -bars h , as 55 shown in the figures referred to.

The "arch-beam," so-called, is, in fact, a part of the frame of the machine and furnishes a convenient means for connecting the frame with the spindle-carrying arms. It will be noted 60 that these arms, which are pivotally connected to the frame of the machine, support the frame, which moves up and down with them, the arms being in turn supported by and pivotally connected with the wheels. Their connection 65 with the coupling-sleeves C is a rigid one,

and thereby whenever their point of attachment to the arch-beam is to one side or the other of the dead-center the springs I act to throw them up or down, as the case may be, and hold them in that position.

70

Having described my improvements and the best way now known to me of carrying the same into practical effect, I state in conclusion that I do not limit myself narrowly to the structural details herein illustrated, for 75 manifestly the same can be varied considerably without departure from the spirit of the invention; but

What I claim herein as new, and desire to secure by Letters Patent, is as follows:

80

1. In a cultivator the combination, substantially as set forth, of the frame, the coupling-sleeves pivotally mounted on the frame, the spindle-carrying arms fast to the sleeves, the wheels mounted on said spindles, the drag-bars and connections between the same and the coupling-sleeves, and spring-actuated means for controlling the vertical position of the drag-bars and holding them raised or lowered, as desired.

90

2. In a cultivator the combination, substantially as set forth, of the frame, the coupling-sleeves pivotally mounted on the frame, the wheels and spindles or stub-axles on which they are mounted, the drag-bars and connections between the same and the coupling-sleeves, and arms attached at one end to the wheel-spindles, and adjustably mounted at the other end so as to be capable of movement relatively to the coupling-sleeves, upon the 100 axis of oscillation of the latter, and means for rigidly securing the arms in their adjusted position.

95

3. The arch-beam and frame, the coupling-sleeves swiveled on the ends of the beam, the 105 spindle-carrying arms, fast to the coupling-sleeves, the wheels mounted on the spindles, the drag-bars and the coupling-arms connecting the drag-bars with the coupling-sleeves, in combination with springs attached at one 110 end to the frame and at the other end to the coupling-arms, arranged substantially as described, to hold the drag-bars down or throw them up, according as the points of attachment of the springs to the coupling-arms and 115 the frame respectively, are in a line below or above the axis of oscillation of the coupling-sleeves, substantially as set forth.

115

4. In a cultivator, the combination with the frame, the coupling-sleeves pivotally mounted 120 on the frame, the spindle-carrying arms fast to the sleeves and the wheels mounted on said spindles, of the drag-bars, the coupling-arms connecting the drag-bars with the coupling-sleeves, springs attached to the frame, notched 125 bars extending downwardly from the coupling-arms, and adjustable connections between the springs and the notched bars, substantially as and for the purposes hereinbefore set forth.

130

5. In a cultivator, a drag-bar composed of two parallel bars, a split box between said bars having cone ends, a coupling-pin held in said box, and bolts for drawing together
5 the two parts of the drag-bar, upon the box and coupling-pin, in combination with the main coupling-arm having a divided end the limbs of which have cone-openings which swivel on the ends of the coupling-pin and fit
10 the cone ends of the box, and means for clos-

ing, and holding closed, the limbs of the coupling-arm, upon the cone ends of the box, substantially as and for the purposes hereinbefore set forth.

In testimony whereof I affix my signature in 15 presence of two witnesses.

SAMUEL NEVIN HENCH.
